(57) **CLAIM**

What is claimed is the ornamental design for a firearm-mounted ammunition holder, as shown and described.

DESCRIPTION

FIG. 1 is a front view of a firearm mounted ammunition holder showing the new design in a flattened state of non-use;

FIG. 2 is a back view thereof;

FIG. 3 is a top view thereof;

FIG. 4 is a bottom view thereof;

FIG. 5 is a left side view thereof;

FIG. 6 is right side view thereof;

FIG. 7 is a left side perspective view thereof;

FIG. 8 is a front view thereof with an open front flap;

FIG. 9 is a front view thereof with an open front flap and a back flap detached from a front surface of a pocket flap to create an open bottom;

FIG. 10 is a front view with an open front flap and a pocket flap laid back on an interior surface of the front flap to expose interior surfaces of the pocket flap and the back flap; FIG. 11 is a left side perspective view with the front flap open and the back flap detached from a front surface of a pocket flap;

FIG. 12 is a front view of the design in a state of use, whereby the article is shown with an opening allowing it to be mounted on a firearm;

FIG. 13 is a back view thereof;

FIG. 14 is a top view thereof;

FIG. 15 is a bottom view thereof;

FIG. 16 is a left side view thereof;

FIG. 17 is right side view thereof;

FIG. 18 is a left side perspective view thereof;

FIG. 19 is a front view of the design mounted on a firearm;

FIG. 20 is a front view thereof with a front flap open; FIG. 21 is a front view thereof with a front flap open and articulated behind a back flap;

FIG. 22 is a perspective view thereof;

FIG. 23 is a perspective view thereof with a front flap open; and,

FIG. 24 is a perspective view thereof with a front flap open and articulated behind a back flap.

(Continued)

The broken lines depicting a firearm and ammunition are directed towards environment and form no part of the claimed design. The broken lines showing stitching do not form part of the claimed design. All other broken lines show portions of the firearm mounted ammunition holder that form no part of the claimed design.
